UNITED STATES PATENT OFFICE.

TRUMAN J. MARTIN, OF ALLENTOWN, PENNSYLVANIA.

ENGINE-STARTING-GEAR LIMITING MEANS.

Application filed February 24, 1921. Serial No. 447,511.

To all whom it may concern:

Be it known that I, TRUMAN J. MARTIN, a citizen of the United States, residing at Allentown, in the county of Lehigh and 5 State of Pennsylvania, have invented certain new and useful Improvements in Engine-Starting-Gear Limiting Means, of which the following is a specification.

The invention relates to limiting means 10 for limiting the movement of a screw fed starting gear on the screw in connection with starting mechanisms for starting combustion engines, wherein the gear is fed into mesh with a gear carried by a fly wheel of the engine and is fed out of mesh on said feed screw by the gear of the fly wheel after the engine is started. It has been found that in starting devices of this 15 character that where the feed gear is limited by coming into engagement with a shoulder or a collar, that the gear is closely jammed against said shoulder or collar by the starting motor and that when the fly wheel and its gear is rotated under control of the engine that this jamming action will not be 20 broken and that the screw sleeve will be twisted off and broken. It has also been found that where the ends of the grooves between the threads of the screw end in 25 oblique angles that the feed gear will also stick and jam and cause breakage when the fly wheel starts.

A further object is to provide radially 30 disposed shoulders on the screw against which shoulders similarly shaped shoulders of the feed gear engage, said radially disposed shoulders and shoulders of the feed gear forming means of preventing jamming of the feed gear to either end of its movement.

A further object is to provide the feed 35 screw and stop collar with radially and longitudinally disposed engaging surfaces for limiting the movement of the feed gear, said surfaces forming means for preventing jamming of the feed gear on the feed screw.

A further object is to provide means for 40 preventing sticking and jamming of the feed gear of a starting mechanism for internal combustion engines, an example of such starting mechanism being shown in Patent No. 1,095,696, dated May 5, 1914.

With the above and other objects in view 45 the invention resides in the combination and arrangement of parts as hereinafter set forth, shown in the drawings, described and

claimed, it being understood that changes in the precise embodiment of the invention may be made within the scope of what is claimed without departing from the spirit 60 of the invention.

In the drawings:—

Figure 1 is a top plan view of the device. Figure 2 is a sectional view taken on line 4—4 of Figure 1.

Figure 3 is a sectional view taken on line 5—5 of Figure 1.

Figure 4 is a sectional view taken on line 6—6 of Figure 1, showing holes drilled into the ends of the feed screw grooves, 70 thereby forming substantially radially disposed stop shoulders for the starting gears.

Referring to the drawing, the numeral 4 designates the starting gear which is fed longitudinally on the threaded sleeve 5 in 75 the usual manner by a self starter when starting an engine, and after the engine has been started, at which time the starting gear moves in the opposite direction in the usual manner. The threaded sleeve 5 is provided 80 with a stop sleeve 12 for limiting the forward movement of the starting gear 4, however it has been found that where the forward end 13 of the starting gear 4 comes into direct engagement with the stop collar 85 12 or the other end of the gear 4 comes into engagement with the ends 15 of the screw grooves, that the starting gear becomes jammed and stuck and upon the starting of the engine this jam is not easily broken and 90 consequently the threaded sleeve is twisted in half, and the starting mechanism considerably damaged. To obviate this difficulty the stop collar 12 is provided with a plurality of shoulders 12^a, which shoulders have radially and longitudinally disposed 95 surfaces 12^b, which surfaces are engaged by similar surfaces 12^c on the starting gear 4. When the starting gear 4 moves on the sleeve 5, in the direction of the arrow b, it will be 100 seen that the engaging surfaces 12^c of the starting gear will come into engagement with the surfaces 12^b of the stop collar and as said surfaces are radially disposed and also longitudinally disposed, it will be seen 105 that it will be impossible for a binding action to take place and consequently when the fly wheel starts to revolve under the power of the engine, the starting gear will immediately rotate on the threaded sleeve 5 until said starting gear is moved out of mesh 110 with the gear teeth of the fly wheel. The

starting gear is prevented from sticking at the end of a reverse direction thereof in the ends 15 of the thread grooves of the threaded sleeve 5 for the reason that the ends 15 of the thread grooves are finished off substantially radially as at 15^a, said finish being formed by boring holes in the ends 15 of the thread grooves, thereby eliminating the usual obtuse finish at the ends of the thread grooves and consequently preventing jamming of the starting gear 4 at that end of its movement.

The invention having been set forth what is claimed as new and useful is:—

15 The combination with a starting gear of an engine starting mechanism, said gear

being fed forwardly and rearwardly on a feed screw and stopped at the ends of its movement, of means for limiting the movement of the starting gear on the feed screw, 20 said means comprising radially disposed engaging surfaces carried by the starting gear and the feed screw, the feed screw radial surfaces being formed by radially disposed round apertures in the screw between the 25 threads at the ends of said threads.

In testimony whereof I affix my signature.

TRUMAN J. MARTIN.
